UNITED STATES PATENT OFFICE.

JAMES KRIVE, OF ST. LOUIS, MISSOURI.

TELEPHONE LATCH.

Application filed August 16, 1926. Serial No. 129,401.

This invention relates to latch devices for the dials of dial telephones.

An object of the invention is to provide a dial latch under control of the receiver 5 hook of a telephone, whereby the dial is engaged and held against manipulation when the hook is held down by the receiver.

Another object of the invention is to provide a latch constructed and designed to 10 operate automatically to engage and hold the telephone dial against manipulation when the receiver is on the hook, and to release the dial so that it may be operated when the receiver is removed from the hook.

15 Other objects will appear from the following description, reference being made to the accompanying drawing in which

Fig. 1 shows one form of the invention in connection with the telephone instrument.

20 Fig. 2 is a cross sectional view on the line 2—2 of Fig. 1.

The telephone instrument shown is of the familiar dial operative type and, as is known, 25 comprises a rotative dial 1 arranged to be successively turned from a starting point by the hand in the direction of the arrow (Fig. 2), and to be returned to its starting point by an actuator not shown forming a 30 part of the dial mechanism. These successive operations indicate the exchange and the station desired.

Telephone instruments also include a 35 pivotally supported receiver hook 2 for supporting the receiver 3, such hook extending into the instrument and being cooperatively related to an actuator, not shown, which raises the hook when the receiver is removed to close the circuit and which is moved downwardly by the weight of the hook to open the 40 circuit.

45 My latch invention for the dial is co-operatively associated with the hook 2 so that when the hook is held down by the receiver 3 the dial 1 is latched against manipulation; and, when the hook 2 rises upon removal of the receiver the latch releases the dial and permits manipulation thereof.

As shown my invention comprises an arm 50 pivoted upon a support 5 and extending to position for engagement with and disengagement from the dial 1. The specific engaging portion shown comprises a part 6 provided with one or more flanges 7 arranged to engage in the holes in the dial 1 when the receiver is on the hook, though the 55 manner and point of engagement of the

latch element with the dial may be varied. The arm or lever 4 is connected by a link 8 with the stem of the hook 2. Preferably the connection of the link 8 with the stem of the hook 2 is adjustable and such connection may be made at any desired point along the stem of the hook by means of a clamping bracket 9 connected with the link and secured to the stem of the hook at the proper point. 60

In the type of telephone instrument shown the invention may be applied thereto by providing the support 5 upon an arm 10 extending from a clamping ring 11 secured to the telephone instrument in such relationship as to obtain proper operation of the latch by the hook of the instrument. Preferably the free end of the arm 4 operates within a 70 guide 12 to prevent the latch from being disturbed by strains to which it may be subjected. 75

From the foregoing it is apparent that when the hook 2 is held down by the receiver 3 the latch device is maintained in latching 80 engagement with the dial 1, preventing manipulation of the dial while the receiver is on the hook; and, that when the receiver is removed from the hook and the hook rises, the latch is automatically disengaged from 85 the dial, permitting use and manipulation of the dial in the usual way.

The specific form and arrangement of the parts may be varied within the whole range 90 of equivalents without departure from the nature and principle of the invention. I do not restrict myself in any unessential particulars, but what I claim and desire to secure by Letters Patent is:—

1. The combination with the hook and the 95 dial of a dial telephone instrument, of a latch operative into and out of engagement with the dial, and a connection operated by the hook for operating the latch to and from engagement with said dial simultaneously with the operation of the hook. 100

2. The combination with the hook and dial of a telephone instrument, of a pivoted latch arranged to be swung into and out of engagement with the dial, and connections operated by the hook for operating the latch to and from engagement with said dial simultaneously with the operation of the hook. 105

3. The combination with the hook and dial 110 of a telephone instrument, of a pivoted latch arranged to be swung into and out of engagement with the dial, and connections operated

by the hook for operating the latch simultaneously with the operation of the hook into engagement with the dial upon movement of the hook to its lower position and out of engagement with the dial upon movement of the hook to its upper position.

4. The combination with the hook and the perforated dial of a telephone instrument, of a pivoted latch operative to and from engagement with the dial in the operations thereof, and a connection operated by the hook for operating said latch simultaneously with the operation of the hook into engagement with the dial as aforesaid when the hook is moved to its lower position.

5. The combination with the hook and the perforated dial of a telephone instrument, of a pivoted latch operative to and from engagement with the dial in the operations

thereof, and a connection operated by the hook for operating said latch simultaneously with the operation of the hook into engagement with the dial as aforesaid when the hook is moved to its lower position and out of engagement with the dial when the hook is raised.

6. The combination with the hook, the dial and the stand of a telephone instrument, of a support detachably connected to the stand, a latch element pivoted upon said support for movement into and out of engagement with the dial, and a link connecting said latch with the hook for moving said latch element to and from engagement with said dial simultaneously with the operation of the hook.

JAMES KRIVE.
